United States Patent Office

Des. 222,254
Patented Oct. 12, 1971

222,254

STORAGE CONTAINER

Harry R. Kattelmann, Oakland, and Guntis Lange, San Leandro, Calif., assignors to Fabricated Metals, Inc.

Filed Sept. 23, 1970, Ser. No. 25,160

Term of patent 14 years

Int. Cl. D23—01
U.S. Cl. D23—2

FIG. 1

FIG. 2

FIG. 3

FIG. 5

FIG. 4

FIG. 1 is a front elevational view of a storage container embodying our new design;

FIG. 2 is a side elevational view thereof;

FIG. 3 is a rear elevational view thereof;

FIG. 4 is a bottom plan view thereof; and

FIG. 5 is a perspective view thereof.

We claim:

The ornamental design for a storage container, as shown.
